RAYON SPINNING MACHINE

Joseph L. Costa, Woonsocket, R. I., assignor to
 Woonsocket Rayon Company, Woonsocket,
 R. I., a corporation of Rhode Island

Application December 2, 1939, Serial No. 307,334

4 Claims. (Cl. 18—8)

This invention relates to rayon spinning machines and, more particularly, to those of the pot spinning type.

As is well known to those familiar with the art, in such machines, in the absence of some compensating mechanism, there is a constant variation in yarn size in the cake spun in the pot, resulting directly from the variation in centrifugal pull exerted on the yarn by the pot. It has heretofore been proposed to compensate for this variation by varying the speed of the Godet wheels from which the yarn is led to the pot, this being accomplished by constantly and very gradually increasing the speed of the shaft driving these wheels. This method, while successful, is, however, disadvantageous in that it leads to considerable inconvenience in doffing and necessitates the use of a large crew in this operation. This is due to the fact that, since all of the Godet wheels of a machine operate at the same speed, and this speed is changed as the cake formation progresses, at the time of removal of the cakes on doffing it is impossible to restore the machine to its initial operating speed until all of the cakes have been doffed.

An important object of this invention is the provision of means whereby the effective speed of the Godet wheels, as regards the pull exerted on the yarn, may be varied while their actual speed remains constant, and this by a structure of such nature that the effective speed of any given wheel may be reduced to the "starting speed" without affecting the effective speeds of any of the remaining wheels.

Another object of the invention is the provision of an apparatus of this character which may be very readily applied to existing machines without materially altering the structure thereof.

Another object of the invention is to produce apparatus of this character which may be readily adapted for imparting a variable tension to the yarn, which may be varied to suit given conditions, and which may be varied independently of the tension exercised by the centrifugal effort exerted by the pot.

A still further object of the invention is the production of an apparatus of this character which may be readily and cheaply manufactured, which is simple in its construction and operation, and which will be durable and efficient in service.

These and other objects I attain by the construction shown in the accompanying drawings wherein, for the purpose of illustration, I have shown a preferred embodiment of my invention and wherein:

Fig. 1 is a fragmentary front elevation of a rayon spinning machine embodying my invention;

Fig. 2 is a section on line 2—2 of Fig. 1;

Fig. 3 is a section on line 3—3 of Fig. 2;

Fig. 4 is a section on line 4—4 of Fig. 3; and

Fig. 5 is a fragmentary side elevation of a modified type of Godet wheel.

The spinning machine fragmentarily illustrated in the drawings includes the usual complement of spinning pumps 10, spinnerets 11, spinning pots 12 and Godet feed wheels 13. As in the ordinary construction, the yarn passes from the spinneret about a guide 14, at present shown as a Godet wheel, to the feed wheel 13 and thence to the pot 12. The Godet feed wheels 13 are driven at the same and a constant speed from a main shaft 15.

These feed wheels, in lieu of being made cylindrical as in the ordinary construction, are provided with a tapered periphery 16, as more clearly shown in Fig. 4, this taper being determined in a large measure by the size and speed of the spinning pot employed and the thickness of the cake to be formed therein. Adjacent the Godet wheel series a shaft 17 is disposed, this shaft being driven at a constant speed which is necessarily, as will hereinafter appear, very slow. I have at present illustrated this shaft as driven from the shaft 15 which drives the Godet wheels through reduction gearing giving to the shaft 17 a very low ratio as compared to shaft 15. As at present shown, the reduction gearing is disposed within a main gear box 18 within which are arranged stub shafts 19, 20, 21 and 22. Stub shaft 19 projects into the Godet housing 23 of the machine and is driven directly from shaft 15. Shaft 19, through shaft 20, drives shaft 21. Shafts 21 and 22 project through the outer face of gear box 18 and are provided at their outer ends with gears 24 and 25 which are made accessible through a removable cover plate 26 for ready changing to permit variation of the speed transmitted by shaft 21 to shaft 22. Shaft 22 directly drives the shaft 17. The gearing connections between shafts 15 and 19, 19 and 20, 20 and 21, and 22 and 17 are preferably of the worm type so that a very high reduction in speed is obtained.

Mounted upon shaft 17 adjacent each Godet wheel is a guide arm 27 which is frictionally engaged with the shaft to an extent insuring its movement therewith but at the same time permitting manual shifting thereof. As at present shown, the upper end of this arm is formed as one-half of a hinged yoke 28, the sections of the

yoke being pressed together about the shaft by means of a spring 29 the tension of which may be adjusted as by means of nut 30. Any other suitable form of friction connection may, of course, be utilized. The lower end of the arm bears a yarn guide 31 through which the yarn is directed prior to its engagement with the Godet wheel. Upon the Godet housing, or any other suitable support, adjacent each arm a stop is mounted, at present shown as comprising a bracket 32 having a lateral finger 33 opposing the outer face of the arm. This stop is made adjustable through an adjusting screw 34 directed through the lateral finger adapted to directly engage the arm 27.

It will be obvious that with rotation of shaft 17 in the direction of the arrow shown in Fig. 4 the arm, if projected outwardly until it engages stop 34, will guide the yarn to a portion of the Godet wheel having a relatively reduced diameter, this being the proper position for the arm at the beginning of the doffing operation. As the doffing continues, the rotation of shaft 17 will progressively move the arm 27 and will serve to constantly guide the yarn to portions of the Godet wheel having greater diameter. When the doffing is completed and the cake is removed from the pot, in order to begin operations it is merely necessary to engage the arm 27 with the hand and shift it outwardly until it re-engages with stop 34. As this is done without interrupting or varying the speed of rotation of shaft 17 in any way, there will be no variation in compensation in other pots on the same machine and it is, accordingly, possible for a relatively small crew to handle the doffing operation.

While I have above described the apparatus as compensating for the change in the centrifugal effort exerted by the pot, it will, of course, be obvious that this variation in tension may be employed for other purposes, and need not be in exact accordance with the variation in centrifugal effort exerted by the pot, or even a direct function thereof. Obviously, the tapered section referred to as employed in the illustration may be varied as, for example, as shown in Fig. 5, wherein the periphery 16a of the Godet wheel 13a is somewhat rounded, the exact formation of the periphery being varied to suit the conditions. In other words, this periphery may assume a variety of forms, all of which, however, will be substantially conical.

Since the construction herein illustrated is, obviously, but one of many forms which the invention may assume, I do not wish to be under- 55

stood as limiting myself thereto except as hereinafter claimed.

I claim:

1. In rayon spinning machinery of the pot-spinning type, a plurality of rotating pots, a Godet wheel associated with each pot and feeding yarn thereto, said wheels having peripheries non-parallel to the axis thereof, a shaft to drive said wheels, a housing enclosing said shaft and supporting said Godet wheels, a second shaft at the exterior of the housing and extending adjacent said Godet wheels, means to slowly rotate said second shaft, a series of independent arms on said second shaft one for each Godet wheel,

15 a thread guide on each of said arms, and a frictional connection between each arm and the second shaft whereby the arms are moved by the shaft to shift the thread guides thereof in the direction of the axes of the associated Godet wheels, said frictional connections being of an order such that each arm may be independently manually shifted about the second shaft without interrupting rotation thereof.

2. In rayon spinning machinery of the pot-spinning type, a plurality of rotating pots, a Godet wheel associated with each pot and feeding yarn thereto, said wheels having peripheries non-parallel to the axis thereof, a shaft to drive said wheels, a housing enclosing said shaft and supporting said Godet wheels, a second shaft at the exterior of the housing and extending adjacent said Godet wheels, means to slowly rotate said second shaft, a series of independent arms on said second shaft one for each Godet wheel, a thread

35 guide on each of said arms, a frictional connection between each arm and the second shaft whereby the arms are moved by the shaft to shift the thread guides thereof in the direction of the axes of the associated Godet wheels, said frictional connections being of an order such that each arm may be independently manually shifted about the second shaft without interrupting rotation thereof, and an adjustable stop associated with each arm and limiting manual shifting of 40 the arm against the frictional connection thereof.

3. The structure of claim 1 wherein the means to drive said second shaft comprises gearing connecting said first and second shafts and includes gears readily accessible for interchangeability to thereby permit regulation of the relative speeds of said shafts.

4. The structure of claim 1 wherein the means to rotate said second shaft comprises irreversible gearing connecting the first and second shafts.

JOSEPH L. COSTA.
